UNITED STATES PATENT OFFICE.

THOMAS M. ADAMS, OF HOUSTON, TEXAS.

PUMP PLUNGER.

1,415,911.

Specification of Letters Patent. Patented May 16, 1922.

Application filed April 11, 1921. Serial No. 460,480.

To all whom it may concern:

Be it known that I, THOMAS M. ADAMS, a citizen of the United States, residing at Houston, in the county of Harris and State 5 of Texas, have invented certain new and useful Improvements in a Pump Plunger, of which the following is a specification.

This invention relates to new and useful improvements in a pump plunger.

10 One object of the invention is to provide a plunger for pumps which has a swiveling connection with pump rod and is formed with spiralled vanes which cause the plunger to rotate as it is reciprocated up and down 15 through the fluid, thus causing its friction with the working barrel to wear it uniformly all around.

Another object is to provide a plunger which is formed of sections which expand 20 against, and closely fit within, the walls of the working barrel.

With the above and other objects in view the invention has particular relation to certain novel features of construction, operation and arrangement of part, an example 25 of which is given in this specification and illustrated in the accompanying drawings, wherein:—

Figure 1 is a plan view of the plunger.

30 Figure 2 is a side view partially in section.

Figure 3 is a plan view of a section of the plunger.

35 Figure 4 is a side view thereof.

Figure 5 is a plan view of a modified form of plunger.

Figure 6 is a side elevation thereof, and

Figure 7 is a bottom end view.

40 Referring now more particularly to the drawings, the numeral 1 refers to the pump rod by means of which the plunger is reciprocated. The lower end of this rod has a head 2 which fits in a socket bearing 3 in the upper end of the stem 4 of the cross head 5. A gland 6 surrounds the rod and is screwed into the bearing 3 and holds said stem against detachment from the rod but permits it to turn relative thereto.

45 The plunger is formed of sections 7, preferably three in number. These sections are arcuate in cross section and when fitted together they form a complete plunger which is tubular in form. Each section has one or more tenons 8 at one edge, and at 55 the other edge corresponding mortises 9, the tenons of each section interlocking with the

corresponding mortises of the adjacent edge of the adjoining section. The sections are thereby held in alignment and they are limited in expansion by the working barrel. 60

The plunger shown in Figures 1 to 4 have the internal annular grooves 10 and 11. The cross head 5 has radiating fingers 12 which engage in said grooves to anchor the plunger to the stem 4. The fingers may be engaged 65 into either one of said grooves, depending upon the length of stroke desired.

The lower end of the plunger is formed into a seat 13 which is controlled by the ball valve 14 in the usual way. In the lower 70 end of the plunger there are spiralled vanes 15. The fluid being pumped passes up through the plunger and the current striking against said vanes causes the plunger to rotate and wear uniformly all around, and 75 the pressure of the fluid will cause the plunger to fit closely against the working barrel and prevent leakage past it.

The modified form shown in Figures 5 to 7 is similar to the other form shown with the 80 exception that the upper ends of the sections are formed into lugs 16 whose inner sides have recesses 17 into which the free ends of the fingers 12 fit to anchor the plunger to the stem. 85

What I claim is:—

1. The combination with a pump rod of a hollow plunger formed of radially movable sections and having a swivelling connection with the rod, a valve seat within the 90 plunger, and a valve controlling said seat.

2. A tubular plunger having spiralled vanes therein, adapted to cause said plunger to rotate when fluid is pumped therethrough, and formed of sections jointed together to 95 expand by internal pressure.

3. A tubular plunger having spiralled vanes therein a pump rod, means connecting the plunger to the rod permitting a relative rotation of the plunger on the rod, said 100 plunger being formed of radially movable sections joined together so as to permit the expansion of the plunger by internal pressure.

In testimony whereof I have signed my 105 name to this specification in the presence of two subscribing witnesses.

THOMAS M. ADAMS.
